UNITED STATES PATENT OFFICE.

GEORGE STAR, OF DAVENPORT, IOWA, ASSIGNOR OF ONE-THIRD TO MARTIN SILBERSTEIN AND ONE-THIRD TO PHILLIP WAGNER, BOTH OF DAVENPORT, IOWA.

CHANGEABLE SIGN.

1,142,777.

Specification of Letters Patent. Patented June 8, 1915.

Application filed July 11, 1914. Serial No. 850,393.

To all whom it may concern:

Be it known that I, GEORGE STAR, a citizen of the United States, residing at Davenport, in the county of Scott and State of Iowa, have invented a new and useful Changeable Sign, of which the following is a specification.

This invention relates to a changeable sign or bulletin board and aims primarily to provide a sign composed of a plurality of similar and superposed slats whereby the sign may be economically manufactured in various sizes.

A further object is to construct a sign of metal, thus insuring a long life for the sign and allowing it to be reconstructed or reassembled, at any time in order to vary its dimensions as desired.

Another object is to provide a sign upon which the letters or characters are detachably hung, the support for the characters being composed of a plurality of superposed and interengaging slats identical in form.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the drawings accompanying this specification and forming a part thereof, the preferred embodiment of the invention has been illustrated.

In said drawings: Figure 1 is a view in elevation of my improved sign. Fig. 2 is a view in perspective of two of the superimposed interengaging and letter supporting slats. Fig. 3 is a cross sectional view taken on the line 3-3 of Fig. 1. Fig. 4 is a cross sectional view taken on the line 4-4 of Fig. 1. Fig. 5 is a view in perspective of one of the hanging character bearing members.

Referring to the drawings in which similar reference numerals designate corresponding parts throughout the several views, the construction comprehends a frame 6 composed of the corner members 7, to which are secured the sides 8, top 9, and bottom 10.

These various frame members have, as illustrated in Figs. 2 and 3, been depicted as substantially semi-cylindrical in cross sectional contour and including a wooden filler or body 11. However, it is to be noted that the exact shape or configuration of these frame members may be varied as desired, the only requisite being that they present a neat and attractive appearance.

The frame members are provided with the rearwardly opening continuous groove 13 extending therearound, to thus receive the various slats and channel members which constitute the support for the character bearing members therein and effect a concealed joint therewith. The support for the character bearing members, which constitute the central portion of the sign, is formed of a plurality of superposed slats 15, extending substantially horizontal, and with their ends disposed within and secured to suitable channels 14, the latter being arranged in an upright manner and secured within the grooves 13 of the side members 8 of the frame. The construction of these slats is illustrated in detail in Fig. 2, wherein it will be observed that each slat is formed with a body portion 16, and with a downwardly and rearwardly projecting flange 17 along the upper extremity thereof. The lower extremity of the body portion 16 carries the downwardly and rearwardly projecting flange 18 the lower extremity of which is bent forwardly to define a shelf 19 adapted to receive and support thereon the flange 17 of a subjacent slat. The free edge of the shelf 19 terminates a distance from the vertical plane of the outer face of the body portion 16 equal to the thickness of the slat material, permitting these faces in subjacent slats to bring in the same vertical plane. A back plate 20 is rigidly secured to the frame members and holds the channels and the slats in their fixed position and rigid relation. The support for the character bearing members will thus be made up of a plurality of spaced vertical faces 21 between which extend the downwardly enlarging recesses 22. This construction allows the reference, or character bearing members to be readily hung upon the upper extremity of each slat or readily detached therefrom.

The character bearing members 23 are in

the nature of strips from the upper extremity of which project the rearwardly and downwardly extending flanges 24, the inclination thereof being substantially equal to, so as to coöperate with, the angularity of the flange 17. By these means the members 23 may be readily positioned upon, and as conveniently detached from, the slats. The character of the information displayed 10 may be varied according to the usage to which the sign is to be placed and the size of the sign may be readily changed by removing the sides 8 of the frame and substituting longer sides therefor and adding 15 a number of slats to those already present in the construction, with suitable channel lengths for the securement of their ends.

Having thus fully described the invention, what I claim is:

- 20 1. A device of the class described, comprising a frame, a plurality of superposed horizontally extending slats depending one from the other and engaged at their extremities by said frame, said slats having 25 their lower portions depressed forming longitudinal recesses, and character bearing members having flanges adapted to project into said recesses.
2. A changeable sign comprising a frame, 30 channel shaped members supported at the sides thereof, a plurality of superposed slats with their extremities disposed within the said channel shaped members, said slats provided with lower rearwardly and down- 35 wardly extending portions defining recesses with the subjacent slats, and a plurality of character bearing members adapted to removably enter said recesses and to extend downwardly therefrom.
- 40 3. A support for sign characters, comprising spaced channel-shaped stiles, a plurality of interengaging superposed horizontally extending slats with their extremities disposed within the said stiles to hold the 45 slats in fixed relation, each slat including a rearwardly and downwardly extending upper flange, a substantially vertical body portion, a rearwardly and downwardly extending flange, and a forwardly projecting shelf 50 carried at the lower extremity of the latter,

said shelf interlocking with and supporting the flange of the subjacent slat.

4. A slat for signs, comprising a plane body portion, the upper extremity of said body portion being bent rearwardly and downwardly and forming a supporting member, the lower edge of the body portion being bent rearwardly and downwardly and forming a flange, the lower edge of said flange being bent forwardly and defining a shelf.

5. In combination, a sign board comprising a series of interengaging slats depending one from the other and provided with interlocking flanges extending from the top and bottom edges thereof, and character bearing members adapted to detachably hang from the top flanges of said slats.

6. In combination, a sign board comprising a series of interengaging slats, each provided with flanges on opposite edges, the flange on one edge extending in an opposite direction from the flange on the opposite edge, adjacent slats being interlocked by means of said flanges and character bearing members adapted to detachably engage and hang from said slats.

7. In a device of the class described, a frame work, slats, depending one from the other, each comprising a body portion, with the front and rear faces of its upper half lying in parallel vertical planes and having, substantially, the lower half bent rearwardly out of the said planes, and a flange extending forwardly from the lower edge thereof and terminating in the vertical plane of the rear face of said upper half, thereby providing a longitudinal recess in the slat; means on the upper portion of each slat adapted to support said slat on the flange of the next slat above, and character bearing members having flanges adapted to project into said recess.

In testimony that I claim the foregoing as my own, I have hereto affixed my signature in the presence of two witnesses.

GEORGE STAR.
